BY

A. L. Vencill ⁶⁵ ATTORNEY.

UNITED STATES PATENT OFFICE.

BURNIE A. STAMP, OF NORTH BRADDOCK, PENNSYLVANIA.

SHIPPING CRATE.

1,410,227.

Specification of Letters Patent. Patented Mar. 21, 1922.

Original application filed March 6, 1919, Serial No. 280,921. Divided and this application filed November 22, 1920. Serial No. 425,675.

To all whom it may concern:

Be it known that I, BURNIE A. STAMP, a citizen of the United States, residing at North Braddock, in the county of Allegheny and State of Pennsylvania, have invented certain new and useful Improvements in Shipping Crates, of which the following is a specification.

My invention relates to knock-down shipping crates. Crates embodying my invention are particularly well adapted for the shipment of chickens and other birds, although they are not limited to this particular use.

One object of my invention is the provision of a knock-down crate which is rugged in construction, yet which occupies the smallest possible amount of space when folded.

The present application is a division of my copending application filed March 6, 1919, Serial No. 280,921, for improvements in shipping crates.

I will describe one form of crate embodying my invention, and will then point out the novel features thereof in claims.

In the accompanying drawings, Fig. 1 is a view showing in side elevation one form of crate embodying my invention. Fig. 2 is a view showing the crate illustrated in Fig. 1 but looking at the latter from the right-hand side. Fig. 3 is a sectional view taken on the line III—III of Fig. 1 and looking in the direction indicated by the arrows. Fig. 4 is a sectional view taken on the line IV—IV of Fig. 2 and looking in the direction indicated by the arrows. Fig. 5 is a view showing a hasp 14 forming part of the crate shown in Fig. 1. Fig. 6 is an end view of the hasp 14. Fig. 7 is a sectional view taken on the line VII—VII of Fig. 5, and showing in detail the locking device of which the hasp 14 forms a part.

Similar reference characters refer to similar parts in each of the several views.

Referring now to the drawings, the crate comprises a bottom member A, two oppositely disposed side members B and B^a, two other oppositely disposed side members C and C^a, and a top member D.

The bottom member A is preferably a flat piece of wood, whereas each of the side members, as here shown, comprises a rectangular frame 2 provided with a number of bars or

slats 3. The top member D may be of any suitable construction.

The two side members B and B^a are attached by hinges H to cleats 5 and 5^a, respectively, which cleats are mounted on the upper surface of the bottom member A. Each of the hinges H is formed (see Fig. 3) by cutting away the cleat 5 except for a centrally disposed pin 6, and passing around this pin a strap 7 of sheet metal the ends of which are attached by screws 8 to a recess in the surface of frame 2. The height of each cleat 5, and the location of the pin 6 are such that when the side members B and B^a are swung inwardly they lie flat against the bottom member A.

The two side members C and C^a are attached to cleats 4 and 4^a by hinges H' which are similar to hinges H. These cleats are higher than cleats 5 and 5^a, however, and are of such height that when the side members B and B^a are folded down against the bottom member, the side members C and C^a may likewise be swung inwardly and will lie flat against members B and B^a.

The top member D is hingedly and slidably attached to the side member C by means which I will now explain, referring particularly to Figs. 2 and 4. The cleat 4 is provided with two notches 10 to accommodate two straps 9, each of which is shaped as shown in Fig. 4. The lower end of each strap passes horizontally through notch 10 and is bent upwardly at its end so that it can be attached by screws 12 to the inner side of the lower strut of the frame of side member C. The upper end of the strap passes horizontally through a slot 11 in the frame of top member D, and is then bent downwardly and attached to the inner face of the frame of side member C by screws 12^a. It will be seen that by virtue of this construction the top member D can be swung upwardly so that it is parallel to side member C, and can then be slid downwardly or telescoped with respect to member C.

The manipulation of the crate is as follows: To fold the crate, the top member D is first swung upwardly and then slid straight down on the straps 9 so that it is parallel with and lies flat against side member C. The side members B and B^a are then folded inwardly until they rest against the bottom member A. The next step is to fold mem-

ber C^a inwardly so that it rests on top of members B and B^a, and the last step is to fold the side member C inwardly, carrying with it the top D, so that member C rests 5 on top of members B and B^a. The top member D then rests flat against members C and C^a, and covers no more area than does the bottom member A.

The crate is opened by a sequence of operations which will be self-evident from the foregoing.

To prevent the crate from collapsing accidentally while in the set-up condition, the slide members are provided with a number 15 of ears 13. Two of these ears are attached to the two ends respectively of each side member C and C^a, as shown in Fig. 1, and project into the path of members B and B^a to prevent the latter members from being 20 swung out beyond vertical positions with respect to the bottom member A. Each side member B and B^a is provided with similar ears 13^b which project into the path of the top member D and so prevent these side 25 members from swinging inwardly from the vertical positions. It will be seen, therefore, that the ears thus far referred to serve to lock the side members B and B^a in vertical positions. It remains only to prevent the 30 side member C^a from swinging outwardly beyond the vertical position, and this is accomplished by ears 13^b attached to the inner surface of the frame of this member, as shown in Fig. 1.

Any suitable means may be provided for clasping the top member D to the side member C^a when the crate is set up. As here shown, this means comprises a hasp 14 and an eyelet 15. The hasp 14 is hinged to the 35 top member D and is provided with a slot 14^a. One corner of the projecting end of the hasp is bent outwardly at right angles as shown at 14^b, and this corner is provided with a hole 14^c. The eyelet 15 is formed 40 as shown in Fig. 7, and comprises a piece of wire passing through a hole in the frame of the side member C^a. The two ends of this eyelet are bent at right angles to the middle portion, and the end having the eye is on 45 the outside of member C^a. To clasp the top member to the side member, the eyelet is turned so that the outer end is in a vertical position, the hasp 14 is then swung downwardly so that the eye projects through slot 50 14^a, and finally the eyelet is swung around until the eye rests against the upturned corner 14^b. The eye then registers with hole 14^c, so that the crate can be sealed, if desired, by passing an ordinary wire seal 55 through the eye and the hole 14^c.

In order to clasp the crate when in knocked-down condition, the cleat 4^a is provided with a second eyelet 15^a (see Fig. 1) which registers with the hasp 14 when the crate is folded, and which co-operates with 65 the hasp in the same manner as eyelet 15.

Although I have herein shown and described only one form of crate embodying my invention, it is understood that various changes and modifications may be made 70 therein within the scope of the appended claims without departing from the spirit and scope of my invention.

Having thus described my invention, what I claim is:

1. A knockdown crate comprising a bottom member, two oppositely disposed side members hingedly attached to said bottom member and arranged to lie flat on the latter when closed, two other oppositely disposed 80 side members hingedly attached to said bottom member and arranged to lie flat on the first two side members when closed, vertically disposed straps attached to the outside of one of said second-mentioned side 85 members and extending over the upper edge of such member, said straps being spaced from the side and from the upper edge of the member, and a top member having holes through which said straps pass, whereby the 90 top member is hingedly and slidably attached to the last mentioned side member.

2. A knockdown crate comprising a rectangular bottom member, two cleats on opposite edges of said bottom member, two side members hingedly attached to said cleats, the cleats being of such height that said side members lie flat on the bottom member when closed and said side members being of such height that they do not overlap when lying flat on the bottom member, two other cleats fixed to the remaining edges of the bottom member and rising above the first cleats, two other side members hingedly attached to the second cleats so as to lie 95 flat on the first mentioned side members when closed, said second side members being of such height that they do not overlap when lying flat on the first side members, vertically disposed straps attached to one of said second side members and spaced outwardly therefrom and extending over the top thereof, and a top member having holes through which said straps pass, whereby the top member is hingedly and slidably attached to the side member having such straps.

In testimony whereof, I affix my signature.

BURNIE A. STAMP.
